PIVOTED LINK JAR CAP WRENCH WITH
RESILIENT SHOES

Henry M. Fredholm, Midlothian, Ill.

Application October 11, 1948, Serial No. 53,910

2 Claims. (Cl. 81—3.44)

1

This invention relates to a jar closure wrench, and is more particularly concerned with a wrench of the self-gripping type which generally embodies curved gripping arms pivotally connected together at two of their adjacent ends and having their other adjacent ends pivotally and slidably connected with a leverage member usually provided by the shank of an operating handle for the wrench.

Various forms of wrenches of this general character have heretofore been provided and proposed. Of the prior constructions of this general form of wrench, some thereof comprise only the relatively rigid arcuate closure encircling arms as the actual closure gripping members. This form of wrench fails to provide maximum efficiency for the reason that the arcuate arms are relatively narrow and accordingly grip the closure in a very limited circumferential area thereof, with a resulting likelihood of denting and therefore damaging the closure and rendering it useless for further use. Furthermore, this form of wrench fails to provide a uniform grip on the closure throughout its circumference even though the two pivoted arms may be truly circular in a given position of the wrench, particularly if the closures vary any in their circumferential contour and extent.

Others of the prior forms of wrenches of this general type comprise various combinations of arcuate arms with other gripping members, but these constructions also fail to provide maximum efficiency which requires that the closure be gripped over a substantial area thereof to prevent damage thereto and also that it be gripped uniformly in a circumferential direction for facilitating easy application of closures to jars as well as their removal therefrom.

It is accordingly a primary object of this invention to provide a jar closure wrench which is of maximum efficiency in operation and which overcomes the above enumerated objections to prior structures of this kind.

A further object of the invention is to provide a jar closure wrench of the self-gripping type which is formed to provide uniform gripping contact with a jar closure over substantial circumferential areas thereof and throughout the entire depth of the closure.

Other objects and advantages of the invention will become apparent in the course of the following detailed description, taken in connection with the accompanying drawing, wherein—

Fig. 1 is a plan view of the improved wrench as observed from one side thereof;

2

Fig. 2 is a view similar to Fig. 1 but showing the wrench in an expanded position and illustrating in particular the action of the pivoted yieldable gripping members in their capability of assuming arcs of a true circle.

Fig. 3 is a plan view of the wrench as observed from the opposite side thereof.

Fig. 4 is a side elevational view of the wrench as observed from below Fig. 1.

Fig. 5 is a side elevational view of the wrench as observed from below Fig. 3, the wrench being here shown on a reduced scale, and as being operatively engaged with a jar closure for applying same to a jar.

Referring now in detail to the drawing, 10 and 11 designate a pair of relatively rigid arcuate arms which are lapped and pivotally connected at adjacent ends thereof as at 12. The other end of arm 10 is pivotally connected at 13 to the free end of shank 14 of an operating handle 15. The shank 14 is provided with an elongated slot 16 and the other end of arm 11 is provided with a headed pin 17 extending through said slot for movement lengthwise thereof. The arms 10 and 11 are relatively thin in directions normal to their planes.

The shank 14 and handle 15 thus provide a lever arm for the arcuate arms 10 and 11 whereby the arcuate arms are caused to expand or contract by their movement about pivot 12 upon movement of the handle 15 in one or the other lateral direction. The wrench further includes a plurality (preferably three) of relatively thin yieldable gripping shoes 18, each of which has suitably secured thereto a bracket 19 which is pivotally secured at 20 to the arm 10 or arm 11.

In the structure as illustrated, the arm 10 is provided with two of the shoes 18, while the arm 11 is provided with only one thereof, but other arrangements clearly fall within the scope of the invention, it being important however that the shoes be arranged with their vertical centers substantially equally spaced around the arcuate arms 10 and 11.

The wrench as shown in Figs. 1 and 4 is engaged with a jar closure for removing same, while the position of the wrench as shown in Figs. 3 and 5 designates a closure being tightened on a jar. It is, of course, necessary that the wrench be reversed from closure applying to closure removing position since the movement of the handle 15 in one direction only causes a gripping action between the shoes 18 and the closure.

The wrench is shown in fully expanded position in Fig. 2 and while this is the closure re-

ceiving position and the arms 10 and 11 must be contracted for firm gripping of the shoes 18 with the closure, the figure has however been used to illustrate the action of the yieldable pivoted shoes 18. In this figure it will be seen that the shoes 18 are all capable of pivotal movement and due to the yieldable characteristics of the shoes 18 they may assume spaced arcs of a true circle designated as C. The closure to be applied or removed is of course smaller in diameter than the circle C, but the action of the shoes 18 as illustrated will prevail when the closure is engaged by the shoes upon contraction of the arms 10 and 11 from the expanded position of Fig. 2 to substantially the positions of Figs. 1 and 3.

This provides for a uniform gripping action of the shoes on the closure or lid of the jar circumferentially thereof whereby the lid is applied to or removed from the jar more easily, and whereby the lid may be tightened with greater certainty. The shoes 18 are preferably of a height at least equal to the depth of the closure or lid as is clearly shown in Fig. 5 wherein the wrench is shown in position for tightening a lid L on a jar J, the shoes preferably extending beyond both sides of the arms. This substantial height of the shoes not only provides for a greater closure gripping area, but it also avoids localized pressure with such resulting damage to the closure as has been experienced with wrenches of this general character heretofore provided or proposed.

While the wrench herein disclosed is particularly adapted for use with the later type of uniform sized jar lids or closures, it is well adapted for use with closures or other circular articles of varying diameters since its construction is such that the gripping shoes readily conform to the surfaces of the closures or other articles due to their pivotal and yieldable action.

While I have disclosed my invention in accordance with a single specific structural embodiment thereof, such is to be considered as illustrative only, and not restrictive, the scope of the invention being defined in the subjoined claims.

I claim:

1. A wrench comprising a pair of relatively rigid arcuate arms having adjacent ends thereof

pivotedly connected, an operating handle including a shank, the other end of one of said arms being pivotedly connected to the shank, the other end of the other arm having a sliding connection with the shank, whereby the arms may be expanded and contracted upon lateral movement of said handle, and a plurality of yieldable arcuate gripping shoes disposed within said arms and pivotedly connected thereto, said arms being relatively thin normal to the planes thereof and said shoes being of substantial dimensions in directions normal to said planes and projecting beyond both sides of said arms.

2. A jar closure wrench comprising a pair of relatively rigid arcuate arms for surrounding a closure to be applied or removed, said arms being relatively thin in the direction of the axis of said closure, said arms having adjacent ends thereof pivotedly connected together, a handle including a shank, the other end of one of said arms being pivotedly connected to the end of said shank, said shank being provided with an elongated slot, the other end of the other arm having a headed pin loosely disposed in said slot, a plurality of yieldable arcuate gripping shoes disposed within said arms, a bracket carried by each of said shoes and including a portion overlying a side face of a respective arm, and pivotal connections between said portions of the brackets and said arms, and said shoes being of relatively thin yieldable material which extends a substantial distance on opposite sides of said brackets and circumferentially of the arms for enhanced yieldable action when engaged with variable diameter closures.

HENRY M. FREDHOLM.
